UNITED STATES PATENT OFFICE.

PAUL MORTIER, OF PARIS, FRANCE, ASSIGNOR TO GENERAL ELECTRIC COMPANY, A CORPORATION OF NEW YORK.

GOVERNING MECHANISM FOR MIXED-PRESSURE TURBINES.

1,060,354.

Specification of Letters Patent.

Patented Apr. 29, 1913.

Application filed July 5, 1911. Serial No. 636,900.

To all whom it may concern:

Be it known that I, PAUL MORTIER, a citizen of the French Republic, residing at Paris, France, have invented certain new and useful Improvements in Governing Mechanism for Mixed-Pressure Turbines, of which the following is a specification.

The present invention relates to governing mechanism for that type of prime mover commonly known as a mixed pressure turbine. Such a turbine is arranged to be supplied with steam or other elastic fluid of low pressure for normal operation and to be supplied with steam or other elastic fluid of higher pressure when the low pressure source fails or is insufficient to supply the demands of the turbine. The low pressure source is depended upon in so far as it is available to the exclusion of the high pressure source because it is less expensive.

A mixed pressure turbine should be so arranged that it can automatically pass from one supply of fluid to the other without change in speed or in the power delivered by the shaft taking place. This is of prime importance where the turbine is arranged to drive an alternating current generator which is connected in parallel with other generators. It is necessary therefore that the governing mechanism of the turbine be adapted, without change of speed taking place and regardless of the respective amounts of fluid supplied by the different sources, to constantly control the admission of fluid to the turbine so as to maintain the speed constant within the limits ordinarily permitted between no load and full load conditions. It is further necessary in order to attain the best results that the governing mechanism shall regulate the participation of each of the two fluids in the production of power, taking into account the available quantity of the low pressure fluid, *i. e.*, the less costly fluid.

My invention has for its object to provide a governing mechanism of improved construction for a mixed pressure turbine, said mechanism being of the type which comprises the feature of putting two obturators in series at the point of entrance of each of said fluids to the turbine, one of said obturators being operated or controlled by a tachometer or speed governor and the other being controlled or operated by a manometric

or other device responsive to the pressure of the low pressure source of fluid supply. The obturators controlled by the speed governor are so arranged that they are moved toward and away from their seats or closed positions simultaneously to regulate the total flow of the two fluids. On the other hand the obturators controlled by the pressure responsive device are so arranged that they control their ports in an opposite sense. That is to say, one obturator opens its port or ports while the other closes its port or ports. As a result of this, the high pressure source will furnish only that portion of the necessary fluid which the low pressure cannot supply, it being understood, however, that the total volume of motive fluid entering the turbine is subject to the control of the speed governor. To state the matter in another way, two primary obturators are simultaneously controlled or moved by the governor in one and the same direction and two secondary obturators located in series with and in advance of the first are so arranged and connected that when one opens the other closes, the action of the secondary obturators being sensitive to variations in pressure of the low pressure source.

In the accompanying drawings which are illustrative of my invention, Figure 1 is a diagrammatic view of a portion of one of my improved governing mechanisms; Fig. 2 is a diagrammatic view also illustrative of the invention; Fig. 3 is a detail view of one form of servomotor; and Fig. 4 is a sectional view of part of a governing mechanism.

1 indicates a high pressure steam chest to which steam is admitted from a boiler or other source by the conduit 2. Located within the chest is a gridiron valve 3 arranged to slide back and forth over the ports 4. This valve or obturator is actuated by a device responsive to the pressure variations of the low pressure source of supply to be described later. Motion from this device is transmitted to the valve by the rod 5. It will be noted that the bridge pieces 6 of the valve are differently spaced and also gradually increase in width from the bottom to the top so that as the valve rises, due to the action of the pressure device, the first or bottom port will open, then the one above and so on. In the downward movement of the valve the upper port closes first, then the

one next below, etc. The chest is also provided with chambers 7, 8 and 9 which receive steam under the control of the gridiron or slide valve 3. The passage of steam from these chambers to the turbine nozzles or other discharging devices is under the control of obturators or valves 10, 11 and 12. These are strung on the rod 13 that is actuated by means of the speed governor or 5 by means under its control. On the rod are collars 14 so spaced with respect to the valves that as the rod 13 moves upward it opens the valve 10 first, then the valve 11 and finally the valve 12. In closing the reverse order is followed, valve 12 closes first, then the valve 11 and finally the valve 10. It is to be noted that valve 3 opens the lowest port first, whereas the rod 13 opens the 10 upper valve first.

15 indicates a low pressure steam chest to which steam is admitted from the exhaust pipe of another engine, from a receiver, re-generator or other source by the conduit 16. In the chest is an obturator or gridiron 20 valve 17 which is mounted on the rod 18 that is or may be a part of the rod 5 and is arranged to move in unison therewith in response to a device sensitive to changes in pressure of the low pressure source to be 25 referred to later. The valve 17 is of the same general character as the valve 3 as are also the ports 19. It is, however, oppositely arranged with respect to its ports. That is to say, as the valve moves upward it first 30 closes the lower port, then the one next above and so on, whereas an upward movement of the high pressure valve opens the lowest port, then the next and so on.

In the chest are chambers 20, 21 and 22 35 to which low pressure steam is admitted under the control of the valve 17. As shown, all of these chambers are open to the steam supply, whereas the high pressure chambers 7, 8 and 9 are cut off. The low pressure ports 19 are so proportioned as to admit the proper amount of steam for low pressure operation when the valve is in the open position and the low pressure source of supply is sufficient. The outlet of steam 40 from the chambers to the turbine is controlled by obturators or valves 23, 24 and 25. These valves are mounted on the rod 26 which may form a continuation of the rod 13 and move in unison therewith. The rod 45 is provided with collars 27 that are suitably positioned with respect to the valves to open and close them successively. The valves are of course larger than the high pressure valves owing to the increased volume of 50 steam. The high and low pressure valves operate in like manner. That is to say, the upper high pressure and the upper low pressure valves both open and close simultaneously by the same direction of movement of the rods 13 and 26, said rods being

moved by a tachometer or speed responsive device, or by means controlled thereby.

The ports of the obturators are of such dimensions that the power developed in the turbine due to the amount of low pressure steam passing through one of the ports 19 to the turbine is equal to the power developed in the turbine due to the amount of steam passing through one of the ports 4. Of course, when the amount of steam received from the low pressure source is only a portion of the total required by the turbine, this proportional variation is produced only on the corresponding portion of the high pressure opening which comprises, 75 in addition to this variable part, a constant opening corresponding to the portion of the steam supply which is required from the high pressure source. Consequently, whatever be the ratio of the valve openings imposed by the manometric device, the power of the turbine will not change when the obturators or slide valves 3 and 17 are moved under the action of said device.

It is to be noted that whatever the relation of the said valve openings, the tachometer or speed governor will simultaneously close or open the admission valves 10 and 23; 11 and 24, and 12 and 25, according to the variations of speed of the turbine. It 90 will further be noted that there will be what may be termed a "composition regulation" (meaning a regulation of the proportions of the two fluids) and a "quantity regulation" (meaning the total quantity or amount of 95 fluid supplied to the turbine), each taking place independently but cooperating to govern the turbine. The "composition regulation" will be determined by the available amounts of low pressure steam due to the pressure responsive device and the "quantity regulation" will be determined by the power requirements as established by the 100 speed governor.

The foregoing description has been directed especially to a turbine having both high and low pressure nozzles or other discharging devices for supplying wheel buckets or blades that are cut into and out of service successively. The following 110 description will be directed to an arrangement in which low pressure steam is admitted to the low pressure portion of the turbine under the control of a throttle valve means, 115 said steam after passing the valve means having access to all the nozzles or other fluid discharging devices in the low pressure portion of the machine.

Referring now to Fig. 2, 34 indicates a high pressure steam chest having passages 125 leading therefrom to nozzles 35 which may be divergent or non-divergent in character as the operating conditions require. These nozzles discharge steam at a suitable velocity and pressure against the buckets or 130

blades 36 on a rotor 37. The passages are provided with valves 38, 39, 40 and 41 which for convenience will be termed primary valves because they act on the steam first. 5 Of these valves 38 opens first and closes last. The passages are also provided with valves 42, 43, 44 and 45 which for convenience will be called secondary valves because they act on the steam after the primary 10 valves. Of these valves 42 opens first on an increasing load and closes last on a decreasing load. The primary valves are sensitive to pressure variations in the low pressure source and the secondary valves to changes 15 in speed of the rotor.

46 indicates the low pressure valve chest and mounted therein is a primary throttle valve 47 which first acts on the steam received from the low pressure source by the 20 conduit 48, and a secondary throttle valve 49 that acts on the steam after it passes the valve 47. Steam is conveyed from the low pressure chest to the nozzles or other fluid discharging devices and to buckets or blades 25 of the low pressure portion of the turbine by the conduit 50. The primary low pressure valve 47 and the primary high pressure valves 38, 39, 40 and 41 are actuated by a manometric device of any suitable construction. 30 In the present instance it comprises a cylinder 51 to which steam is admitted from the low pressure source by the conduit 52. Within the cylinder is a piston 53 whose under side is exposed to the pressure 35 of the low pressure steam. The upper side of the piston is exposed to atmospheric pressure and is or may be weighted by a spring 54. The piston is connected to the primary low pressure valve 47 by the rod 55. Pivotally connected to the rod by a fork and pin is a lever 56 pivoted at 57. The right hand end of the lever is connected by a rod to the rack 58, the latter meshing with a pinion 59 on the rock-shaft 60. On the shaft are 40 mounted the primary high pressure valves 38 to 41, inclusive, the valve 38 opening first, then the valve 39 and so on. As a result of the mechanism described, it will be seen that all of the primary valves are 45 moved by the manometric device.

61 indicates a tachometer or speed governor mounted on the shaft 62 that is driven by the rotor 37. The connection between the rotor shaft and the governor shaft may be 50 of any suitable form.

63 indicates a lever that is pivoted at 64 and is actuated by the sliding collar of the governor. To the lever is pivoted the rod 50 connected with the secondary low pressure valve 49. 65 indicates a lever pivoted at 66 and actuated by the collar of the speed governor. To the lever is pivotally secured a rod that actuates the rack 67 which in turn meshes with a pinion 68 mounted on the rock-shaft 69, the latter opening and closing

the secondary high pressure valves 42 to 45 successively, the valve 42 opening first, then the valve 43 and so on.

In connection with the tachometer and its obturators or valves and the manometric device and its obturators or valves any ordinary form of servo-motor may be employed to relieve the load thereon, said motor being actuated by steam, hydraulic, electric or other power. Both the tachometer and manometric device may be of any suitable form or construction as best suits the requirements in any given case. 70 75

In Fig. 3 is shown a suitable servo-motor operated hydraulically. It comprises a piston 31 and its cylinder and a pilot valve 32 to which is attached a rod 33 that may be actuated by the speed governor or by the pressure responsive device. The rod of the piston 31 may actuate a valve directly or indirectly through a cam and lever, as shown in Fig. 4. The main valve of such an apparatus is to relieve the speed governor and pressure responsive device of a large amount of work whereby they can be made more 80 85 sensitive. 90

In Fig. 4 is shown a suitable arrangement of the valves for the high pressure portion of the turbine. 30 indicates the high pressure steam chest and 38 one of the primary valves. This valve is provided with an upright stem having a collar at the top. Engaging with the collar is a pivoted lever 70, the free end of which has a roller that rides on the cam 71. The cams for all the valves are mounted on a shaft which is actuated by a servo-motor under the control of the manometric device. A spring 72 is arranged to close the valve 38 when permitted to do so by the lever 70. 42 indicates one of a 100 number of secondary valves which is provided with an upright stem having a collar at the top that engages with a pivoted lever 73. The lever is actuated by a cam 74 which in turn is moved by a servo-motor under the 105 control of the speed governor 61. A spring 75 serves to close the valve when permitted to do so by the cam 74. 110

Assuming a suitable supply of low pressure steam and constant load, the operation 115 of my improved mechanism is as follows, referring particularly to Fig. 2: Low pressure steam enters by the conduit 48 and passes the valves 47 and 49, the valve 47 being responsive to the pressure of the low 120 pressure source due to the manometric device, and valve 49 being responsive to the load on the turbine due to the action of the tachometer 61. The valves 38 to 41 will occupy positions determined by the manometric device and valves 42 to 45 will occupy 125 positions due to the tachometer. For any constant load, assuming the low pressure supply to be sufficient, the speed governor keeps the valve 49 open by an amount suffi- 130

cient to satisfy the load on the turbine, and also keeps one or more of the high pressure valves 42 to 45 open. On the other hand, the pressure responsive device keeps the valve 47 wide open and closes all of the valves 38 to 41. If now the pressure of the low pressure source of supply decreases, the piston 53 will descend carrying with it the low pressure throttle valve 47. This same action working through the lever 56, rack 58, gear 59 and rock-shaft 60 will cause one or more of the valves 38 to 41 to open admitting high pressure steam to one or more of the passages leading to the nozzles. The valves are opened in the following order: 38 first, then 39, and afterward 40 and 41. The reduction in the supply of low pressure steam requires that the speed governor shall open one or more of the secondary high pressure valves 42 to 45 inclusive and also close the secondary low pressure valve 49 by a proper amount. The power delivered by the turbine will remain the same but instead of receiving low pressure steam only, it will be driven by a mixture of high and low pressure steam, the high pressure or more costly steam supplying only that portion of the total energy which the low pressure cannot.

The main difference between Figs. 1 and 2 resides in the fact that whereas in the former case the low pressure steam is admitted by successively operating valves to each nozzle or group of nozzles, in the latter case the admission is simultaneous to all of said nozzles but the total amount is regulated by throttling.

The pressure responsive device and speed governor shown in Fig. 2 can obviously be used to actuate the distributers, obturators or valves of the other figures. So also can the servomotor of Fig. 3.

It should be noted that the valve means controlled by the speed governor operate at once and in the same sense; that is to say, for a given load, the governor simultaneously opens passages to each vapor on the high and low pressure sides which could, if they were effectively supplied (in the absence of apparatus controlled by the pressure device), furnish in the form of high or low pressure steam, an identical quantity of energy which is equal, for a single fluid, to the total quantity necessary.

It should be further noted that the valve means controlled by the pressure device should divide the work between the two fluids by reason of the pressure which is available in the low pressure source, only requiring the aid of the high pressure source when the supply from the low pressure source is deficient. For this reason the valve means responsive to the low pressure source should, without taking into account the real load on the turbine, present a total opening for the two fluids such that the power fur-

nished would be equal to the maximum power of the turbine, if the openings were effectively utilized, instead of being in part controlled by the action of the valve means controlled by the governor.

At full load the valve 49 is wide open and consequently the valve 47 begins to reduce the energy as soon as it begins its closing movement. On the contrary at light load the valve 49 is only partly open producing the throttling of the steam necessary to the reduction of power. Consequently, if the valve 47 closes, its effect upon the energy furnished will not make itself felt immediately, but only after a certain stroke. There is then a delay in its action which should be repeated on the high pressure side in order that the high pressure admission may not be modified too soon, since this would result in an increase of power.

Care should be taken to see that the opening of valve 47 or of 49 will permit the delivery of the amount of steam necessary for full load conditions when the turbine is supplied with low pressure steam only. Likewise when all the valves 38 to 41 and 42 to 45 are open, they should permit the delivery of the amount of steam necessary for full load conditions when the turbine is supplied with high pressure steam only.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. In combination, a turbine, sources of low and high pressure fluid supply therefor, a secondary obturator means for successively opening and closing passages admitting high pressure fluid to the turbine, a secondary obturator means for regulating the supply of low pressure fluid to the turbine, a speed governor that controls both of said secondary obturator means, primary obturator means that control the passages of low and high pressure fluid to said secondary means, and a device responsive to the pressure of the low pressure fluid for actuating the primary obturator means.

2. In combination, a turbine, sources of low and high pressure fluid supply therefor, a secondary obturator means for successively opening and closing passages admitting high pressure fluid to the turbine, a secondary obturator means for regulating the supply of low pressure fluid to the turbine, a speed governor that controls both of said secondary obturator means, a primary obturator means for successively opening and closing the passages admitting high pressure fluid

to said secondary high pressure obturator means, a primary obturator means for regulating the supply of low pressure fluid to the secondary low pressure obturator means, 5 and a device responsive to the pressure of the low pressure fluid for controlling both of the primary obturator means.

3. In combination, a turbine, sources of low and high pressure fluid supply therefor, 10 a secondary obturator for successively opening and closing ports admitting high pressure fluid to the turbine, a secondary obturator for throttling the supply of low pressure fluid to the turbine, a speed governor that controls both of said secondary 15 obturators, primary obturators that control the passage of low and high pressure fluid to the secondary obturators, and means for actuating the primary obturators.

4. In combination, a turbine, sources of fluid supply therefor that differ as to pressure, a chest containing passages, a valve means for opening and closing the passages successively, a second valve means for opening and closing said passages successively, 25 a second valve chest, a pair of throttle valves in the second chest, a means for actuating one of said valve means in the first named chest and also one of the throttle valves, and a means for actuating the other of said 30 valve means and one also of said throttle valves.

In witness whereof, I have hereunto set my hand this 21st day of June, 1911.

PAUL MORTIER.
